[57] CLAIM

The ornamental design for a chair, as shown and de-
scribed.

DESCRIPTION

FIG. 1 is a front perspective view of a chair showing
my design.

FIG. 2 is a side perspective view of the design of the
instant invention.

FIG. 3 is a rear perspective view of the design of the
instant invention.

The side of the chair not shown is a mirror image of the
side shown in FIG. 2.
